CLAIM

I claim the ornamental design for a baby carrier, substantially as shown and described.

DESCRIPTION

FIG. 1 is a perspective view of a baby carrier showing the new design;

FIG. 2 is a front view of a baby carrier showing the new design;

FIG. 3 is a rear view of a baby carrier showing the new design;

FIG. 4 is a left side view of a baby carrier showing the new design;

FIG. 5 is a right view of a baby carrier showing the new design;

FIG. 6 is a top view of a baby carrier showing the new design;

FIG. 7 is a bottom view of a baby carrier showing the new design;

FIG. 8 is a perspective view of the baby carrier showing the new design with the hood deployed;

FIG. 9 is a front view of the baby carrier showing the new design with the hood deployed;

FIG. 10 is a rear view of the baby carrier showing the new design with the hood deployed;

FIG. 11 is a left side view of the baby carrier showing the new design with the hood deployed;

FIG. 12 is a right side view of the baby carrier showing the new design with the hood deployed;

FIG. 13 is a top view of the baby carrier showing the new design with the hood deployed; and,

FIG. 14 is a bottom view of the baby carrier showing the new design with the hood deployed.

The dotted lines show claimed stitching on the baby carrier. The dashed lines showing a design on the baby carrier are for illustrative purposes only and form no part of the claimed design. Surfaces of the carrier between dashed lines that do not have straight line shading form no part of the claimed design.
